(57) **CLAIM**

The ornamental design for a combined shot glass and bottle opener, as shown.

DESCRIPTION

FIG. 1 is a front elevational view of a combined shot glass and bottle opener showing my new design;
 FIG. 2 is a left side elevational view thereof;
 FIG. 3 is a top plan view thereof;
 FIG. 4 is a right side elevational view thereof;
 FIG. 5 is a bottom plan view thereof;
 FIG. 6 is a cross-sectional view showing a section taken along line 6-6 of FIG. 4;
 FIG. 7 is a front isometric view thereof;
 FIG. 8 is a top isometric view thereof; and,
 FIG. 9 is an exploded view thereof.
